ASPIRATOR PUMP

John J. Madine, Sr., Vineland, N. J., assignor to
Ace Glass Incorporated, Vineland, N. J., a cor-
poration of New Jersey

Application March 18, 1943, Serial No. 479,657

5 Claims. (Cl. 230—101)

This invention relates to aspirator pumps of the type used to produce partial vacua for any purpose but particularly for use in evacuating vacuum tubes.

Another object is to furnish an aspirator pump capable of employing mercury, oil or other vaporizable liquid having suitable vapor pressure, and which liquid is converted to vapor state and the vapor forced through jets at a rapid rate; the rate varying with the dimensions of the pump.

The invention also consists in other features and advantages which will appear from the following description and upon examination of the drawing.

The structures containing the invention may partake of different forms that may be varied in their detail and may be made of various materials, preferably glass. To illustrate a practical application of the invention, I have selected a pump embodying the invention, as an example of the various structures and modifications thereof that contain the invention, and will describe the selected structure hereinafter, it being understood that variations may be made without departing from the spirit of the invention. The particular structure selected, as an example, is shown in the accompanying drawing, in which:

Fig. 1 is a side elevation of the complete pump.

Figs. 2 and 3 are enlarged transverse horizontal sectional views taken on the lines 2—2 and 3—3 respectively of Fig. 1.

Fig. 4 is a vertical sectional view of the vapor jet in the booster side of the pump.

Referring to the drawing in which the pump is shown as made of glass or any other suitable transparent material, 10 designates a closed reservoir adapted to contain mercury or any other suitable liquid, and provided with a dome-shaped bottom portion 11 designed to receive any suitable type of heating means.

A vapor discharge pipe 12 rises from the reservoir and is branched to provide a first passage-way or tube 13, and a second passage-way or tube 14. These tubes extend upwardly respectively into a first conduit 15 and a second conduit 16, the tube 13 rising to a considerably greater height than the tube 14. The conduits are the arms of a U-shaped member 17 and the tubes extend through the bottom of this member, which bottom forms a sump 18 from which condensate may be drained through a pipe 19 leading back to the tube 12. A trap 20 is preferably interposed in the pipe 19.

The conduit 15 forms the pusher or down-draft side of the pump and is surrounded by a jacket

21 so as to provide a space 22 from which a coolant may be discharged through a nipple 23. The coolant is introduced into the lower portion of the space 22 through a pipe 24, leading from a space 25 provided by jacket 26 which surrounds the conduit 16 of the booster side of the pump. A nipple 27 may be arranged at the lower end portion of the jacket 26 for introducing the coolant. The upper end of the tube 13 is closed, as indicated at 28 and the wall of the tube is provided below this end with one or more sets of apertures 29 for discharging vapors into the conduit 15. A pair of umbrella-like deflectors 30 surround the tube and overlap lengthwise thereof so as to form a flaring mouth 31 through which the vapors are directed downwardly and against the cooled wall of the conduit 15. Obviously such structure will permit down-draft within the conduit, and the condensate formed will gather in the sump 18 to be returned to the reservoir.

The conduit 16 is of Venturi shape and the tube 14 terminates at the throat 32 thereof. The end of the tube is obstructed but not closed, by a conical deflector 33 (Fig. 4), the largest diameter of which is about equal to the outside diameter of the tube 14. This deflector which is arranged at the throat, extends into the tube and is joined to the latter by a radially arranged support 34. It directs the vapors against the cooled walls of the conduit 16.

The gas which is evacuated is drawn into the conduit 15 through a hollow extension 35, connected to the upper end of the conduit by a dome 36. A similar dome 37 is connected to the top of the conduit 16, and a discharge or exhaust pipe 38 is connected to this dome and has an elbow end 39 terminating within the dome adjacent the side wall thereof.

It will be obvious that the elements are all joined where necessary by gas tight joints.

In operation, mercury or the like in the reservoir 10 will be heated and the resultant vapors from this single reservoir will flow into both tubes 13 and 14. The vapor discharged through the holes 29 will be directed downwardly so as to cause a downdraft in the conduit 15, to propel gases entering at 35, through the pump. As the vapors travel downwardly they will be condensed and returned to the reservoir.

At the booster side of the pump the vapors discharged from 14 will travel up the Venturi conduit 16 and will thus boost the gases which will eventually be discharged through 38. Of course the vapors discharged from the tube 14 will be

condensed in the tube 16 and will flow back to the sump 18.

Persons skilled in the art will readily recognize the utility and method of utilization of such a pump in the production of partial vacua so it is unnecessary to elaborate further in this connection. They will also recognize that any suitable number of holes 29 and deflectors 30 may be arranged in the down-draft side of the pump. In like manner, the up-draft side of the pump may have more than a single jet if desired.

An important feature of the pump resides in the jets used. These differ from those of prior design in that they produce a directed vapor flow of increased velocity against the cooled walls, thus increasing efficiency. These jets are of one general type and two designs, one of which is a modification of the other. The general type is that of two or more concentric conical-shaped deflectors, between which are vapor outlets, the conical-shaped pieces directing the flow in the desired manner. By varying the dimensions of these conical pieces and the distance separating them, the velocity of flow as well as the direction of flow may be controlled to a satisfactory degree. Other variables are the size and shape of the vapor outlets. The jet at the bottom of the up-draft side 16 is a special case of those appearing on the down-draft side, for while the outside conical piece 33 is spaced from the internal condensing wall, it is nevertheless a part of the jet.

It will be recognized that the conical pieces need not be exactly concentric, that is to say, the walls of the cones need not be parallel in order to obtain the desired effect. To further define this type jet it may be stated that at least part of one cone should extend into the other. It may be further stated that the shape of the deflectors 30 may be hemispherical, pyramidal or the like without departing from the invention.

By employing a single reservoir and a single drain pipe, I can use a single heater for vaporization with resulting economies in the installation and manufacture of the pump.

What I claim is:

1. An aspirator pump comprising a reservoir adapted to be heated and to contain a volatile liquid, a substantially vertically disposed Venturi conduit through which a gas is to be propelled, having an upwardly flaring portion, means for directly cooling said conduit, a passage-way rising from the reservoir into the conduit and terminating below the throat of the venturi and, also, below said upwardly flaring portion, means positioned at the throat for deflecting vapors from the passage-way against the cooled conduit, and means for discharging the condensate from the vapors from said conduit.

2. An aspirator pump comprising a reservoir adapted to be heated and to contain a volatile liquid, a substantially vertically disposed Venturi conduit through which a gas is to be propelled, having an upwardly flaring portion, means for cooling said conduit, a passage-way rising from the reservoir into the conduit and terminating below the throat of the venturi and, also, below said upwardly flaring portion, means positioned at the discharge end of the passage-

way for deflecting vapors against the cooled conduit, and means for discharging the condensate from the vapors from said conduit, said deflecting means comprising a substantially bi-conical member extending downwardly into the discharge end of said passage-way.

3. An aspirator pump comprising a reservoir adapted to be heated and to contain a volatile liquid, a U-shaped member forming down-draft and up-draft conduits through which a gas is to be propelled, means for cooling said conduits, another U-shaped member rising from the reservoir and forming passageways discharging into the conduits, the portions of the passage-ways which extend into the conduits being spaced from the walls thereof and having means for discharging jets of vapor into the conduits, deflectors cooperating with the last mentioned means for directing vapors respectively downwardly in the down-draft conduit and upwardly in the up-draft conduit and against the cooled conduits, and means for discharging condensate from the vapors from said first-mentioned U-shaped member into the reservoir.

4. An aspirator pump comprising a reservoir adapted to be heated and to contain a volatile liquid, a U-shaped member forming down-draft and up-draft conduits through which a gas is to be propelled, the up-draft conduit having a Venturi-shaped portion means for cooling said conduits, another U-shaped member rising from the reservoir and forming passageways discharging into the conduits, the portions of the passage-ways which extend into the conduits being spaced from the walls thereof and having means for discharging jets of vapor into the conduits, the means for discharging vapors into the up-draft conduit being arranged below the throat of the venturi, and deflectors cooperating with the last mentioned means for directing vapors respectively downwardly in the down-draft conduit and upwardly in the up-draft conduit and against the cooled conduits.

5. An aspirator pump comprising a reservoir adapted to be heated and to contain a volatile liquid, a U-shaped member positioned above the reservoir and forming down-draft and up-draft conduits through which a gas is to be propelled, means for cooling said conduits, another U-shaped member rising from said reservoir and forming passageways discharging into the conduits, the portions of the passage-ways which extend into the conduits being spaced from the walls thereof and provided with means for discharging vapor into the conduits, deflectors cooperating with the last mentioned means and directing vapors respectively downwardly in the down-draft conduit and upwardly in the up-draft conduit and into contact with the cooled walls thereof, the up-draft conduit being restricted at the place where the vapors enter the same and having a portion flaring upwardly from said place, a sump at the bottom of the first-mentioned U-shaped member communicating with the lower ends of the conduits, and a passage-way for returning condensate from the sump to the reservoir.

JOHN J. MADINE, SR.
